UNITED STATES PATENT OFFICE.

WILLIAM C. WEBB, OF ATLANTIC CITY, NEW JERSEY.

ELECTRIC SIGN.

1,386,822.

Specification of Letters Patent. Patented Aug. 9, 1921.

Application filed May 7, 1921. Serial No. 467,596.

To all whom it may concern:

Be it known that I, WILLIAM C. WEBB, a citizen of the United States, residing at Atlantic City, in the county of Atlantic and 5 State of New Jersey, have invented certain new and useful Improvements in Electric Signs, of which the following is a specification, reference being had to the accompanying drawings.

10 This invention relates to electric signs, and particularly to those signs in which electric lamps are disposed in a trough which is formed in the shape of a letter, character, emblem, scroll or other device to be illuminated, this trough being painted with the predominating color of the letter.

15 The general object of the present invention is to provide a construction of this character which has an illuminated border of a color contrasting with or harmonizing with the color of the letter itself.

20 And a further object is to provide an illuminated letter comprising an inner trough-shaped body within which electric lamps are disposed, an outer trough-shaped body defining a border around the letter, the interior of which is painted of a contrasting color to that of the interior of the first named trough-shaped body, and provide 25 means whereby the light of the lamps disposed in the first named body may be directed against the painted interior of the second trough-shaped body.

30 Other objects will appear in the course 35 of the following description.

My invention is illustrated in the accompanying drawings, wherein:—

Figure 1 is a front elevation of an illuminated letter constructed in accordance with 40 my invention, the illuminated letter forming part of a sign;

Fig. 2 is a longitudinal sectional view thereof;

Fig. 3 is a cross section on the line 3—3 45 thereof.

Referring to these figures, 10 designates the base of the letter, which may be of any suitable character and of any suitable color. Upon this base is disposed a trough-shaped body 11 which is made of metal and which is provided with sockets 12 for the reception 50 of the electric lamps 13 in the usual manner. The interior of this trough-shaped body 11 may be painted white or any other desired color. Exterior to the wall of the trough-shaped body 11 is an outer wall 14 which

may have the same form as that of the body 11, though this is not an absolute necessity, and the interior of this body 14, that is the exterior of the body 11, and outer 60 wall of the body 14 are to be painted of a color contrasting with or harmonizing with the color used on the interior of the body 11.

The wall of the body 11 is pierced at intervals, as at 15, so that light from the lamps 65 13 will be directed against the bottom and side walls of the exterior trough-shaped body and illuminate these walls. Preferably these openings 15 are disposed adjacent the bottom of the body 11 so that a good illumination 70 will be secured at the bottom of the border. I do not wish to be limited to any particular shape for these openings 15, though preferably they are circular, but they might be of any desired shape which would 75 perform the function of permitting the light from the lamps 13 to be discharged against the bottom of the border. Preferably the wall of the inner trough-shaped body 11 will be lower than the outer wall 14, and under 80 ordinary circumstances there is about $\frac{1}{2}$ " difference between the two walls. The lamps 13 project outward beyond the edge of the wall of the body 11 so that these lamps will illuminate the upper margin of the outer 85 wall 14. Obviously as many lamps as may be desired may be disposed within the body 11, and obviously the form, proportions and number of the openings 15 may be varied within wide limits. Obviously the shape of 90 the wall of the body 11 and the wall of the body 14 may be changed in a large variety of ways.

I have illustrated my invention as being embodied in the letter "I," but I do not wish 95 to be limited to this, as it is perfectly obvious that any other letter might be so embodied or any desired numeral might be so embodied, or that this method of forming letters might equally well be applied to the 100 formation of any other desired figure, character or emblem.

With this construction, the middle portion of the letter is brilliantly illuminated in the usual manner, while surrounding this 105 illuminated middle portion there is a partially illuminated border of a color harmonizing or contrasting with the highly illuminated portion. Thus assuming that the bottom and inside face of the sides of the 110 trough-shaped body are painted white and that the outer face of the wall of the body

11, the inner face of the wall 14 and the bottom of the space between the wall 14 and the wall 11 are painted yellow, then upon the energizing of the lamps a letter will be presented having a brilliantly illuminated white central portion with a more or less golden or yellow border. If the light from the lamps 13 was not discharged against the border, this border would not show its color and would simply show as a band of shadow surrounding the central, brilliantly illuminated portion, but by providing the perforations 15 and by making the wall of the body 11 lower than the wall of the trough-shaped body 14, the light of the lamps will be discharged against the colored surface which constitutes the border, and thus this colored surface will be illuminated and the border will not be a mere band of shadow but will have the quality of an illuminated border.

It will be noted that this construction provides for an illuminated letter or figure in which the central portion of the letter or figure is brilliantly illuminated, while the border has a modified illumination so that the border in a sense has a half-tone value relative to the middle or center of the letter or figure. Furthermore, in daylight the outer and inner walls define between them a border which is more or less in shadow because of the fact that the outer and inner walls are relatively close together as compared to the distance across the inner trough-like member, and thus even in the daylight the letter is well defined by its border of more or less shadow.

I claim:—

1. An illuminated figure for electric signs comprising an inner, approximately trough-shaped body, an outer trough-shaped body surrounding the first named trough-shaped body and extending slightly beyond the latter, and illuminating means disposed within the inner trough-shaped body, there being perforations through the wall of the

inner trough-shaped body adjacent the bottom thereof whereby the light of said lamps may be discharged into the space between the outer and inner bodies to thereby illuminate the walls of said space. 50

2. An illuminated figure for electric signs comprising an inner, approximately trough-shaped body, an outer surrounding trough-shaped body, the inner face of the inner trough-shaped body having a certain color and the walls of the space defined by the outer trough-shaped body and the inner trough-shaped body having a contrasting color, and lamps disposed at intervals within the inner trough-shaped body, the wall of the inner trough-shaped body having openings adjacent the bottom thereof through which the light of said lamps is discharged into the space between the inner and outer bodies and against the bottom of said space. 60

3. An illuminated figure for electric signs comprising an inner, approximately trough-shaped body, an outer surrounding trough-shaped body, the inner face of the inner trough-shaped body having a certain color and the walls of the space defined by the outer trough-shaped body and the inner trough-shaped body having a contrasting color, and lamps disposed at intervals within the inner trough-shaped body, the wall of the inner trough-shaped body having openings through which the light of said lamps is discharged into the space between 70 the inner and outer bodies, the inner body having its wall of slightly less height than the wall of the outer body, the lamps projecting beyond the wall of the inner body 75 but not beyond the wall of the outer body 80 whereby the light of said lamps will be directed against the upper portion of the outer wall of the outer trough-shaped body. 85

In testimony whereof I hereunto affix my signature.

WILLIAM C. WEBB.
